(57) **CLAIM**

I claim the ornamental design for a cord lock assembly, as shown and described.

DESCRIPTION

FIG. 1 is a front elevational view of a first part of a cord lock assembly;

FIG. 2 is a rear elevational view of the first part of the cord lock assembly;

FIG. 3 is a left side view of the first part of the cord lock assembly;

FIG. 4 is a right side view of the first part of the cord lock assembly;

FIG. 5 is a bottom plan view of the first part of the cord lock assembly;

FIG. 6 is a top plan view of the first part of the cord lock assembly;

FIG. 7 is a perspective view of the first part of the cord lock assembly;

FIG. 8 is a front elevational view of a second part of the cord lock assembly;

FIG. 9 is a rear elevational view of the second part of the cord lock assembly;

FIG. 10 is a left side view of the second part of the cord lock assembly;

FIG. 11 is a right side view of the second part of the cord lock assembly;

FIG. 12 is a bottom plan view of the second part of the cord lock assembly;

FIG. 13 is a top plan view of the second part of the cord lock assembly;

FIG. 14 is a perspective view of the second part of the cord lock assembly;

FIG. 15 is a front elevational view of the cord lock assembly;

FIG. 16 is a rear elevational view of the cord lock assembly;

FIG. 17 is a left view of the cord lock assembly;

FIG. 18 is a right view of the cord lock assembly;

FIG. 19 is a bottom plan view of the cord lock assembly;

FIG. 20 is a top plan view of the cord lock assembly; and,

FIG. 21 is a perspective view of the cord lock assembly.

The broken lines are included for the purpose of showing portions of the article and form no part of the claimed design.
